P. BELVIN

HEATING AND VENTILATING APPARATUS

Filed June 1, 1925

By

Lacy, Lacy, Attorneys

UNITED STATES PATENT OFFICE.

PRESTON BELVIN, OF RICHMOND, VIRGINIA.

HEATING AND VENTILATING APPARATUS.

Application filed June 1, 1925. Serial No. 34,134.

To all whom it may concern:

Be it known that I, PRESTON BELVIN, a citizen of the United States, residing at Richmond, in the county of Henrico and 5 State of Virginia, have invented certain new and useful Improvements in Heating and Ventilating Apparatus, of which the following is a specification.

This invention relates to improvements in 10 heating and ventilating apparatus and has as one of its objects to provide an apparatus of the class referred to especially adapted for the heating and ventilating of school rooms and similar places of assembly, where 15 economy in space is desirable and where it is necessary to provide a constant supply of fresh air to the room at a suitable temperature and constantly remove the foul air.

The apparatus embodying the invention 20 includes a heating unit, such for example as a coal stove, although any other kind of fuel may be consumed by selecting an appropriate unit, and a drum which substantially encloses the heating unit and in connection 25 with which there are provided certain pipes and conduits for the purposes of ventilation and carrying off the foul air, as will be presently explained, and one of the objects of the invention is to so construct 30 the drum that no live coals or ashes from the heating unit or stove can fall to the floor within the drum to cause fire, and likewise so construct the drum that free access may be had to the doors of the stove and so that 35 a part of the stove will be exposed in a manner to permit of pupils attending the school, drying their clothing and warming their feet.

Another object of the invention is to so 40 construct the apparatus that the heat from the stove will be utilized to advantage in not only delivering to the room a continuous supply of fresh air, but also to continuously remove, from the vicinity of the floor, the 45 foul or vitiated air without, however, creating any annoying drafts in the room.

In the accompanying drawings:

Figure 1 is a view partly in elevation and 50 partly in vertical section illustrating the apparatus embodying the invention installed.

Figure 2 is a front elevation of the heating unit and drum of the apparatus.

Figure 3 is a horizontal sectional view 55 taken substantially on the line 3-3 of Fig-

ure 1, looking in the direction indicated by the arrows.

The heating unit of the apparatus is indicated in general by the numeral 1 and comprises any appropriate type of stove 60 such, for example, as the upright heating stove 2 shown in the drawings and which stove is provided with the usual fire-box door 3 and ash-pit door 4, the stove being supported with its base 5 in somewhat elevated position above the floor of the room in which the apparatus is installed, by the usual legs 6. The floor of the room is indicated by the numeral 7 in Figure 1 of the drawings and, in accordance with the principles of the invention, an opening 8 is formed in the floor directly beneath the stove, and a grating 9 is arranged within the opening. The numeral 10 indicates a fresh air conduit which may be of wood, 75 metal, or any other material found suitable for the purpose and may be of any desired construction and dimensions, this conduit being closed at its inner end and extending beneath the floor 7 with its said inner end 70 in communication with the opening 8. The other end of the conduit is placed in communication with an opening 11 formed in the wall 12 of the building in which the apparatus is installed, and a screen 13 is 80 preferably positioned upon the outer side of the wall 12 to extend over the outer end of the opening 11 and prevent the entrance of vermin into the conduit 10.

The heating unit 1 is enclosed within a 90 drum 14 which is preferably of sheet metal and substantially cylindrical, being of a diameter greater than the diameter of the stove and having an opening 15 formed in its wall and defined by side plates 16 which 95 extend inwardly from the wall of the drum and have their free vertical margins cut away to conform to the contour of the stove proper so that their said margins will contact the body at opposite sides of the front 100 thereof. A plate 17 extends inwardly from the wall of the drum at the upper side of the opening in the drum and the inner edge portion of this plate extends beneath the usual rim or flange 18 at the top of the stove. A similar plate 19 extends inwardly from the wall of the drum at the lower side of the opening and at its inner edge projects 105 beneath the rim of the base 5 of the stove. In this manner, the front of the stove is 110

sufficiently exposed in the opening in the front of the drum to permit of full benefit being derived from the heat thrown off directly from the stove, for the purpose of permitting pupils to warm their feet and dry their clothing in inclement weather, the major portion of the stove, however, being surrounded by the drum, and the plates 16, 17 and 19 constituting baffles to prevent escape of heat from the interior of the drum. The drum is suitably secured to the floor 7, as indicated by the numeral 20, and is open at its top.

The numeral 21 indicates a stove pipe which leads from the top of the stove 2, in the usual manner, and is provided with the usual damper 22. This pipe is connected by an elbow 23 with a pipe 24 which extends horizontally within the upper side 20 of a preferably cylindrical shell 25 which is fitted at one end into an opening 26 formed in the wall 12 and communicating with the flue or chimney 27, the end of the pipe 24 preferably terminating substantially flush 70 with the said end of the shell. The other end of the shell is closed as indicated by the numeral 28, except for an opening 29 through which the pipe 24 is introduced. The numeral 30 indicates a foul air conduit 30 or pipe which, at its upper end, is in communication with the lower side of the shell 25 adjacent the closed end 28 thereof, the lower portion of the conduit 30 extending downwardly into the drum 14 in rear of the stove 2 and relatively close to the said stove so as to be heated thereby. A damper 31 is arranged in the conduit 30, and the conduit is provided at its lower end with an intake branch 32, extending at substantially 40 right angles therefrom and through an opening 33 formed in the wall of the drum 14, near the bottom thereof.

From the foregoing, it will be evident that the hot gases and products of combustion rising through the smoke pipe 21 and passing through its branch 24, will issue from the end of the branch into the flue or chimney 27, thus creating an up-draft in the foul-air conducting pipe or conduit 30, causing the air near the floor of the room in which the apparatus is installed, to be drawn in

through the intake 32 and delivered through the shell 25 into the chimney flue 27. It will likewise be evident that inasmuch as the lower portion of the foul-air conducting pipe 55 or conduit 30 is located within the drum 14, it will be subjected to a high degree of temperature and, therefore, the upward passage of foul air will be greatly facilitated and the room more thoroughly ventilated. It 60 will also be found that, inasmuch as the heating unit is substantially enclosed within the drum, an up-draft will be created within the drum serving to draw in fresh air through the screen 13 and opening 11 and by way of 65 the conduit 10, to be heated in the drum and delivered through the open top thereof and into the room. Furthermore, by providing the drum with the baffles or shields 16, 17 and 19, no hot coals or ashes can fall to 70 the floor of the room within the confines of the drum. At the same time, a portion of the surface of the heating unit is directly exposed to the atmosphere of the room so that pupils standing in front of the apparatus 75 may warm their feet and dry their clothing in inclement weather.

Having thus described the invention, what I claim is:

In a structure of the character described, 80 a stove including a body having fire-box and ash pit doors and means to support the body in spaced relation to a floor, a drum disposed about said stove in spaced relation thereto and open at its top and of a height 85 to extend above the stove, said drum having an opening formed therein of a size to expose the portion of the stove provided with the fire-box and ash pit doors, plates extending inwardly from the sides of said 90 opening in converging relation to each other and having close fitting engagement with the stove, and plates extending inwardly from the upper and lower ends of said opening and respectively having close fitting engagement with the stove above the fire-box door 95 and below the ash pit door, the side plates constituting reflectors for directing heat outwardly from the stove.

In testimony whereof I affix my signature.

PRESTON BELVIN. [L. s.]
